United States Patent Office.

C. L. W. BAKER AND L. S. HILLS, OF HARTFORD, CONNECTICUT, ASSIGNORS
TO LESTER S. HILLS AND GEORGE D. JEWETT.

Letters Patent No. 64,736, dated May 14, 1867.

IMPROVED SHOE-BRUSH.

The Schedule referred to in these Letters Patent and making part of the same.

TO ALL WHOM IT MAY CONCERN:

Be it known that we, CHARLES L. W. BAKER and LESTER S. HILLS, of Hartford, county of Hartford, and State of Connecticut, have invented certain new and useful Improvements in Shoe-Brushes; and to enable others skilled in the art to make and use the same, we will proceed to describe, referring to the drawings in which the same letters indicate like parts in each of the figures.

It consists of a tube or tubes, in combination with the fluid-brush for conducting the fluid from the fluid-receptacle into said brush. In the accompanying drawings—

Figure 1 is a vertical sectional view of this invention.

A is a metallic brush-holder and blacking-receptacle; *a* is a handle; *c* is the blacking-receptacle; *d* are flanges for holding the brushes; *e* are the brushes; *e'* is the blacking-brush; *h* are tubes through which the blacking flows from the receptacle into the brush *e'*, which are secured in the upper side of the cap of the receptacle directly under the brush *e* and inside of the flange *d*, the upper end of which extends up through the wood into the brush. *i* is a tube secured to the under side of the cap of the receptacle directly under the tube or tubes *h*, having an opening or openings which communicate directly with the tube or tubes *h*, the inner end of which is open into the chamber of the receptacle *c*; the outer end is secured through and flush with the outside of the receptacle *c*. This tube is provided with a plug, *k*, which is fitted closely and works freely in the tube *i*. This plug is provided with a groove, *l*, formed in one side thereof, so that when the groove *l* in said plug is turned up against the opening of the tube or tubes *h*, a free passage will be opened for the flow of the blacking from the receptacle into the brush. *n* is a screw cap, which opens or closes the orifice in the end of the handle *a*, or it may be located in any other desirable place for the purpose of supplying the receptacle. By withdrawing the plug *k* it will be convenient to supply the receptacle with fluid or blacking through its tube *i*, and thereby avoid the necessity of using the plug *n*. *e* is a polishing-brush, secured inside of the flange *d*. By the use of this brush, the work of blacking boots and shoes is rendered less irksome, the brush itself may be kept in better order, the blacking preserved from waste by exposure and evaporation, is susceptible of being packed in a trunk with clothing without liability of soiling it, and though last not least, it produces a tasty and desirable article for use and trade. We believe we have thus shown the nature, construction, and advantage of this improvement, so as to enable others skilled to make the same therefrom.

We claim the stopper *k* with the tube or tubes *h*, brushes *e* *e'*, and receptacle *c*, substantially as and for the purpose described:

CHAS. L. W. BAKER, [L. S.]
LESTER S. HILLS [L. S.]
